[57] CLAIM

The ornamental design for a cartesian coordinates type robot, as shown.

DESCRIPTION

FIG. 1 is a front, top and right side perspective view of a cartesian coordinates type robot showing our new design;

FIG. 2 is a rear, bottom and left side perspective view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a right side elevational view thereof; and

FIG. 8 is a left side elevational view thereof.

*Fig. 1**Fig. 2**Fig. 3**Fig. 4**Fig. 5**Fig. 6**Fig. 7**Fig. 8*
